Atty.

UNITED STATES PATENT OFFICE.

CARL G. OSTEMAN, OF SOUTH BOSTON, MASSACHUSETTS, ASSIGNOR TO S. A. WOODS
MACHINE COMPANY, A CORPORATION OF MAINE.

PLANING-MACHINE.

1,240,769.

Specification of Letters Patent. Patented Sept. 18, 1917.

Application filed June 23, 1916. Serial No. 105,499.

To all whom it may concern:

Be it known that I, CARL G. OSTEMAN, a citizen of the United States, and resident of South Boston, county of Suffolk, and 5 State of Massachusetts, have invented an Improvement in Planing-Machines, of which the following description, in connection with the accompanying drawings, is a specification, like letters on the drawings representing 10 like parts.

My present invention is an improvement in planing machines and its object is to improve and perfect such machines. More particularly the invention relates to means, 15 preferably automatic, to control the relative operative position of a plurality of cutter heads and the stock being operated upon in the machine, whereby both sides of the stock will be acted on or planed to a predetermined 20 size, when the stock is full thickness, but when the stock is scant, only one of the surfaces will be acted upon and when the stock is equal to or below this predetermined thickness it will pass through with- 25 out being acted on by either cutter head. Heretofore planing machines have been arranged for one cutter head to remove the surplus stock on one side while the other is set to take off a fixed amount on the other 30 side and therefore when the stock is scant it is not held firmly during feeding by the second cutter resulting in inferior and unsatisfactory work.

The object of my invention is to obviate 35 these difficulties and to automatically vary the cut of the second cutter and at all times to hold the stock firmly while being operated upon by this cutter. Thus as long as the first cutter head is doing work and the stock 40 is thick enough for the second cutter to have its full cut, both plane the stock to its finished thickness. But when the stock is too thin for both to cut, it is held free from the first head and is then forced up immediately before the second head and held free of it also. When the thickness is only sufficient to be trimmed by one cutter head, then it is held down free of the first cutter head, while the second cuts it to the required finished extent, and while being thus trimmed 45 the stock is held firmly in place against the top guide or pressure bar. Furthermore, my invention contemplates the provision of automatic means, preferably actuated by the 50 varying thicknesses of the stock itself to in-

sure the bottom cutter planing off the bottom surface where the thickness permits, and where the stock is too thin for both top and bottom cutters to plane their respective surfaces, then to so control the action of 60 both cutters and stock as to eliminate the planing action of both. I accomplish this object, in the particular instance above mentioned, by means of a tilting platen so constructed and arranged in combination 65 with the top and bottom cutters and the rest of the machine as to provide that both cutters will engage the stock on their respective sides when the stock is of suitable thickness, while the platen will be oscillated 70 when relatively thin portions of the board or thin boards are presented, permitting a less cut for the bottom head, and guiding its lower surface momentarily away from, or even clear of, the action of the lower cutter, if stock is less than finished thickness, until a surplus thickness in the stock is again 75 presented for planing.

Further objects of the invention are to provide a simple construction, capable of a 80 wide range of adjustments and suitable to be incorporated in present types of planing machines without materially altering the structure or operating parts.

Further details, advantages, and novel 85 combinations of parts will be hereinafter pointed out and claimed.

Referring to the drawing illustrating in a cross section a preferred embodiment of the invention, I have shown a fragmentary 90 portion only of a planing machine, eliminating the bearings, operating parts, and the like, for clarity of description.

As illustrated, a top cutterhead 1 and lower cutterhead 2, such as are ordinarily 95 employed in planing machines to act on the top and bottom surfaces respectively of a board or other stock to be planed, are shown in cross section. Knives or cutters 3 held in respective positions by keys 4 and bolts 5 are shown of usual form. Portions of 100 the frame of the planing machine are indicated at 6 and 7 at the front of the planing cutters and at 8 and 9 at the rear, stock shown in dotted lines at 10 being fed 105 through the machine from right to left, viewing the drawing, in the direction of the arrow. It will be understood that the various adjustments of cutters, guides, etc., for thickness of stock to be planed, and the like, 110

may be of any usual and well-known construction and are not herein shown in detail.

At the front of the machine the frame 6 is formed with an inclined portion 11, on which a table 12 having similarly inclined bearings 13 and 14 is mounted, said table carrying an oscillating platen 15 which acts as a lower guide and support for the stock 10 as the same is fed into the cutters 1 and 2. The table 12 has projecting flanges 16 and 17 at either end, forming corresponding recesses or grooves 18 and 19, and carries a bearing member 20 arranged in a position substantially under the top cutter 1, which 15 constitutes a rocking bearing for the platen 15, member 20 fitting into a squared recess 21 in said platen. The top surface of the bearing 20 is rounded, as shown at 22, in order to allow for the free oscillation of the 20 platen 15 thereon. At the inner end 23 of the oscillating platen is a depending flange 24 adapted to engage and strike against the overhanging end 17 of the table 12, while at the other end of said platen is a lug 25 25 secured to the platen by a bolt 26 in order to facilitate assembling, with a rib 27 arranged to fit within the recess 18 and engage the flange 16 when said platen is rocked. The length of the lug 25 and rib 30 27 is preferably sufficient to permit the desired scope of oscillation in the platen 15 on its bearing 20, together with the space provided in the formation of the lug 24, for such oscillation.

35 Rear guides 28 and 29 adjustably secured by bolts 30 and 31 to frame portions 8 and 9 respectively, are shown to receive the stock from the first cutter 1 and guide it in its feeding or planing or both by the second 40 cutter 2. At the other end secured to the portion 7 is a top guide or chip breaker 32 arranged to slide vertically against the tension of a coiled spring 33 bearing on a lug 34, which lug also acts as one of the 45 sliding guides on said portion 7. The spring 33 is arranged around the rod 35, tapped or otherwise secured in the portion 7 and carrying a washer 36 and a pair of nuts 37 on its outer end to adjust 50 the tension of said spring, thus normally forcing the guide 32 downwardly, sliding on said member 7, as shown at 38 and 39, and putting the stock 10 under immediate tension as the same is fed into the machine between the chip breaker 32 and tilting platen 15. A curved metal plate 40 is preferably secured to the front of the guide 32 by a bolt 41, as shown.

60 In the operation of the apparatus, the mechanism is first adjusted to receive and plane surplus stock of desired size and to a predetermined thickness. The cutters may be adjusted and the table 12 moved on the inclined support 6 to similarly adjust the 65 top surface of the oscillating platen 15.

When a board 10 is fed into the mechanism it first bears between the plate 40 and the front portion of the platen 15, lifting the chip breaker 32 against the tension of its spring 33. This action holds the forward portion of the platen 15 firmly seated upon the top of the flange 16. The continued feeding of the board 10 then subjects its top surface to the planing action of the cutters 3 on the cutterhead 1 and further feeding action of the board, if of suitable thickness to be planed by both top and bottom cutters, rocks the inward portion 23 of the oscillating platen 15 downwardly as the board is fed under the guide 28 and subjects the bottom surface to the cutterhead 2. Thus both top and bottom of the stock are planed. If, however, the board has thinner places, or thinner boards are fed in, the chip breaker 32 may hold the stock clear of the cutter 1 and the surplus stock be only taken off by the second cutter 2, the platen 15 rocking on the member 21 and raising the nose 23 to hold the stock firmly against the presser bar 28 during the cutting action of the second cutter 2. Thus the platen 15 is in effect a second chip breaker acting in coöperation with the cutter 2, but preferably being actuated by the spring 35. In fact it is within the scope of my invention to employ any automatic means, whether separately actuated or coöoperating so long as the varying thicknesses of stock are taken care of and held firmly while each cutter acts upon the stock.

It will be appreciated that my invention is not limited to details of construction herein illustrated, nor to top and bottom planing cutters, but may have other fields of usefulness, and I consider it to be broadly novel to provide automatic mechanism which will enable one cutter, at all times, to act on a predetermined portion of stock, irrespective of the thickness of said stock and irrespective of whether or not one or more cutters are acting thereon, which other cutters will perform their cutting action whenever required to bring the stock down to a predetermined thickness.

My invention is further described and defined in the form of claims as follows:—

1. In apparatus of the kind described, a pair of planing cutters adapted to work on opposite sides of stock, means to feed said stock by said cutters and automatic means to guide said stock into cutting action with one cutter and simultaneously control the cutting action of the other cutter according to the thickness of the stock operated on, said means consisting in the yieldingly actuated chip breaker, a rocking guide upon which said chip breaker presses, with the inner end of said guide acting as an independent chip breaker in combination with the second cutter.

2. In apparatus of the kind described, a pair of planing cutters adapted to work on opposite sides of stock, means to feed said stock by said cutters, a chip breaker in advance of the first cutter automatic means to guide said stock into cutting action with the second cutter and hold the stock firmly during the cutting action of the second cutter, said automatic means consisting in a tilting platen to guide the stock from one cutter to the other said platen being acted upon by the chip breaker and tilted to an extent allowed by the thickness of the stock.

3. In apparatus of the kind described, top and bottom planing cutters adapted to plane the top and bottom surfaces of stock fed by them, a tilting guide arranged with its pivot substantially under the top cutter and in advance of the bottom cutter, stops to limit the tilting movement of said guide, and yielding means adapted to contact with the top surface of stock fed through the apparatus to oscillate said tilting guide within the limits afforded by said stops, a varying extent corresponding to the varying thick-

ness of said stock, and thereby to control the planing action of the cutters, and a fixed guide opposite the bottom cutter against which the tilting guide presses the stock.

4. In apparatus of the kind described, top and bottom planing cutters adapted to plane the top and bottom surfaces of stock fed past them, a fixed guide opposite the bottom cutter, a tilting guide opposite to and coöperating with the top cutter and adapted to be actuated on a pivot directly under the axis of the top cutter, a portion of said tilting guide extending over the fixed guide opposite the bottom cutter, a yieldingly actuated chip breaker arranged to coöperate with said tilting guide and actuating said guide to constitute a second chip breaker on the fixed guide.

In testimony whereof, I have signed my name to this specification, in the presence of two subscribing witnesses.

CARL G. OSTEMAN.
